FREQUENCY-CHANGING METHOD AND MEANS

Application filed May 1, 1924. Serial No. 710,282.

This invention relates to method and means for rectifying current and more particularly to a method and means applicable to rectification of house lighting or 110 volt alternating current to direct current of proper voltage for use in connection with radio receiving apparatus. Frequent efforts have been made to employ the usual house lighting current as the source of current for 5 radio receiving apparatus, but use of said current has resulted in a humming in the radio apparatus, due primarily to the pulsations in the house lighting current. Use of alternating house lighting current has presented the greatest difficulty because of the comparative low frequency of the alternations, that is, usually 60 cycles, which is in the range of audibility and therefore objectionable as the source of electric supply 10 for radio receiving apparatus. However, alternating current has a number of advantages such as economy, ease of transformation from one voltage to another, and the very important advantage that it is always 15 ready to use.

The objects of the present invention are to provide a transforming method and means which may be employed with radio receiving apparatus without a resulting hum due to 20 the alternations of the house lighting current employed; to set up radio frequency oscillations; to obtain a flow of current of constant high frequency potential from said radio frequency oscillations; to employ a grid circuit 25 in the frequency changing tubes; to secure simplicity of construction and operation, and to obtain other advantages and results as may be brought out in the following description.

Referring to the accompanying drawing to 30 which reference will be had in the following description the figure illustrates diagrammatically the method and means for changing the frequency of alternating current in 35 accordance with my invention.

In the specific embodiment of the invention illustrated in said drawing, the reference numerals 1 and 2 represent the input wires for the apparatus, to supply house 40 lighting current thereto such as the usual

60 cycles 110 volt alternating current. These wires are connected to the opposite ends of a primary 3 of a multiple transformer. For convenience I have shown a secondary 4 having a center tap 5 which in 55 effect amounts to two secondaries. Another secondary 6 is provided for lighting the filaments as will be hereinafter explained.

From the outer ends of secondary 4 I make connection to the plates 7 of a pair of transforming tubes 8. In each such connection between secondary and plate is interposed a high frequency choke coil 9. Each plate is also connected to one end of an output primary 10 the other ends of which are connected to opposite sides of a condenser 11. Condenser 11 will not pass the 60 cycle or 60 input current, but will pass current of radio frequency.

Associated with output primary 10 is an 65 output secondary 12 which I have shown for convenience as in two sections with the inner ends connected by wire 13. The outer ends of this output secondary 12 are connected by wires 14 to the filaments of radio receiving 70 apparatus (not shown). Preferably a condenser 15 is connected across the outer end connections of said output secondary. Another secondary 16 is associated with output primary 10 for purposes hereinafter mentioned.

The tubes 8 have, in addition to plates 7, each a filament 17 and a grid 18. I have shown the corresponding filament terminals connected and the connections separately 85 joined with the opposite ends of the light secondary 6 of the input transformer. One of the filament connections, as 19, is also attached to one side of an absorbing condenser 20 the other side of which is in circuit with 90 the center tap 5 of the input secondary. The other filament connection 21 is in circuit with a resistance or grid leak 22 in turn connected with a center tap 23 from the secondary 16 of the output transformer. The outer ends 95 of said secondary 16 are connected to the grids 18, thus obtaining a push and pull oscillator. Oscillation established in the grid circuit sets up radio frequency in the rectified current flowing through the grid 100

and plate to filament which is therefore free to pass through the otherwise interrupting condenser 11, thus obtaining the radio frequency current in the output transformer and setting up the output current in the secondary 12 to the radio receiving apparatus. Emphasis is to be laid on the fact that choke coils 9 prevent the high frequency current from going back through the input secondary 4 and condenser 11 prevents the low frequency current from short circuiting through the output primary. The output current from output secondary 12 is suitable for lighting a filament in a radio receiving apparatus, but may be and is preferably passed through a further rectifier so as to obtain a low voltage rectified current if desired. I have not deemed it necessary to specifically show a rectifier from the output secondary 20 as any suitable type of rectifier may be used.

Attention is to be called to the fact that the absorbing condenser is charged at all times by the rectified current, the positive side of the condenser being toward the filament and the negative toward the center tap of the transformer secondary. For taking off a further supply of rectified current, leads 24, 25 may be connected from opposite sides of the absorbing condenser 20. One lead, as 30 25, may have a variable resistance or potentiometer 26 at the end thereof connected across to the other lead 24. From the potentiometer 26 connection is made with a choke coil 27 beyond which is a condenser 28 across 35 to the other lead and then a further choke coil 29 for trapping and filtering the undesirable pulsations and thus enabling the device to operate as the source of supply for direct current.

Obviously detail changes and modifications may be made in the manufacture and use of my improved method and means for rectifying alternating current, and I do not wish to be understood as limiting myself to the exact structure shown except as set forth in the following claim when construed in the light of the prior art.

Having thus described my invention, I claim:

50 In an alternating current frequency changing system the combination with a source of low frequency current of a plurality of vacuum tube oscillators connected to said source, a high frequency output circuit connected to said oscillators and a low voltage circuit inductively related with said high frequency output circuit, the inductive relation being effected by a transformer having a primary of two portions connected through a low frequency choking condenser and another primary winding connected in the grid filament circuit of the oscillators.

CHARLES V. LOGWOOD.
